L. ATWOOD.
INTERNAL COMBUSTION ENGINE.
APPLICATION FILED FEB. 24, 1921.

1,418,351.

Patented June 6, 1922.

Inventor,

Leonard Atwood;

By *A. B. Leapham*,
Attorney.

UNITED STATES PATENT OFFICE.

LEONARD ATWOOD, OF BOSTON, MASSACHUSETTS.

INTERNAL-COMBUSTION ENGINE.

1,418,351.

Specification of Letters Patent. Patented June 6, 1922.

Application filed February 24, 1921. Serial No. 447,496.

To all whom it may concern:

Be it known that I, LEONARD ATWOOD, a citizen of the United States, and a resident of Boston, in the county of Suffolk and 5 Commonwealth of Massachusetts, have invented certain new and useful Improvements in Internal-Combustion Engines, of which the following is a full, clear, and exact specification.

10 This invention relates to the type of engine set forth in my companion applications filed August 27, 1920, and Numbered 406,329 and 406,330, wherein the packing rings are inlaid in the wall of the combustion chamber instead of in the periphery of the piston, and are located at the lower end of the chamber. Since the piston head must descend below the packing rings in order to 15 permit the exhaust to escape, the rings will 20 spring out into injurious engagement with the piston when it ascends, unless means are provided for preventing it.

For such prevention, I have devised two somewhat different means, one consisting in 25 providing the head of the piston with an annulus rising therefrom externally continuous with the periphery of the piston, but perforated close above the piston-head to permit the escape of the exhaust. The other 30 consists in vertically grooving the upper part of the piston's periphery to reach the exhaust ports, while keeping the piston head just above the rings.

I further improve the engine by perforating 35 the lower end of its piston in order that the lubricating oil in the crank case and which will be splashed against the piston's interior at its down stroke, will pass through to and lubricate the piston's exterior surface.

40 In the drawings forming part of this specification, Fig. 1 is a central vertical section of an engine embodying my improvements. Fig. 2 is a perspective view of its piston. Fig. 3 is a horizontal section of the 45 piston extension. Fig. 4 is a perspective view of another form of the piston.

The reference numeral 1 designates the piston of the engine; 2, the explosion chamber; 3, the lower section of the cylinder; 4, 50 a jacket surrounding the explosion or combustion chamber 2, and 5, the crank case. The combustion chamber is spaced at its lower end from the upper end of the lower section 3, thereby forming an annular channel 55 for the exhaust, the latter escaping therefrom through a suitable conduit 6,

To the lower end of the combustion chamber 2 is secured an annulus 7 for holding in place a set of packing rings 9 adapted to press inward against the periphery of the 60 piston 1 and thereby prevent the escape of the charge past the latter.

So long as the head 9 of the piston is above these packing rings, the latter are all right, but after the head has descended below the rings to deliver the exhaust to the pipe 6, and rises again into engagement with the packing rings, then there is liable to be trouble; for, since the rings will have sprung inward as soon as the piston descended below them the edge of the piston will strike the rings. If, now, the edge of the piston were tapered off in order force the rings back in again, the latter would be subjected to an amount of wear, both 70 from the engagement with the piston and from their shunting back and forth in their seats and in contact with each other, that would rapidly render them incapable of 75 performing their designed function.

What I have done, therefore, has been to provide a means for preventing any such centripetal movement of the packing rings when the piston descends below them. My preferred means consists of a flange 10 rising from the upper end of the piston and having its outer diameter the same as that of the piston, the height of this flange being sufficient to rise just above the packing rings, or even a trifle below the upper side of the 80 top-most ring.

Through this flange 10 are several holes 11 located therein to be on a level with the exhaust annular channel 8 when the piston is at its lowest point. Thus arranged, the 85 exhaust can pass freely through these openings 11 to the channel 8 and thence to the pipe 6, and still the packing rings are retained exactly as they are when the piston itself is contacting with them.

To reduce the compression chamber when the piston is at its upper extreme, the head 12 of the combustion chamber is centrally depressed, as at 13, leaving a restricted annular space 14 for the reception of the 100 flange 10.

In the form of piston illustrated in Fig. 4, the piston itself is elongated and grooves 15 are longitudinally cut in the upper surface of the same down to a depth which will 110 provide ample communication with the channel 8 when the piston is at its lowest limit,

Of course, in this form of the piston the cylinder head 12 is not centrally depressed.

A further improvement in the piston is the provision of a series of holes 16 radially through it near its lower end, so that when the piston sinks to its lower limit, the lubricating oil deposited in the crank case 5 will be splashed therefrom by the action of the crank, up against the interior of the 10 piston and will largely pass therefrom through the holes 16 into contact with the interior of the cylinder section 3 and thereby will lubricate the same and the exterior of the piston. Any excess of the oil will be 15 removed from the exterior of the piston by a wiping ring 17 kept in place by an annulus 19.

There is no need for lubrication in the combustion chamber 2 for the reason that it 20 is larger in diameter than the piston and consequently there is no friction between the same.

Additional lubrication for the piston in the lower section of the cylinder may be provided, as from a reservoir 20 connected by 25 a pipe 21 to the section 3, but ordinarily the oil delivered through the perforations 16 is sufficient.

In this form of engine, the fuel oil is 30 designed to be delivered through a pipe 22 and thence between the packing rings 9 into contact with the surface of the piston as the latter rises, so that by the time the piston reaches the upper extremity of its 35 stroke, this oil has been entirely vaporized by the heat and is then ignited by the compression. The air for admixture with the vapor is supplied through a pipe 23, serving also to aid in the expulsion of the exhaust; 40 all as set forth more fully in my companion application Serial No. 406,330, filed August 27, 1920.

What I claim is:

1. An engine comprising a cylinder provided with packing rings intermediate of 45 its length, and a piston reciprocative therein, the exhaust port of the cylinder being close beneath said rings, and the piston being provided with means for retaining 50 said rings in place within the cylinder when the piston is at its lower limit and uncovering said exhaust port.

2. An engine comprising a cylinder provided with centripetally pressing packing rings intermediate of its length, an annular 55 exhaust channel close beneath said rings for permitting the escape of the exhaust, and a piston movable in said cylinder, the piston having apertures communicating both with the space immediately above the top of the 60 piston and with said exhaust channel when the piston is at its lowest limit, and means for holding the packing rings from springing inwardly when said piston is at said limit. 65

3. An engine comprising a cylinder provided with inwardly pressing packing rings intermediate of its length, an annular channel close beneath said rings for the discharge 70 of the exhaust, and a piston movable in said cylinder having a closed head at its upper end, and an apertured flange rising from said head, the apertures permitting access to said channel and the flange retaining said rings from springing inwardly. 75

4. An engine comprising a cylinder provided with inwardly pressing packing rings intermediate of its length, and an exhaust port close beneath said rings, and a piston having a closed head reciprocative in the 80 cylinder, the piston having a flange rising from said head of the same diameter as the exterior of the piston and adapted to remain in contact with said rings when the piston is at its lowest limit and the piston 85 head is below the level of said exhaust port, said flange having an opening through it to communicate with said port at the same time.

5. An internal combustion engine comprising a cylinder provided with inwardly pressing packing rings intermediate of its length and an annular exhaust channel close beneath said rings, and a piston having a 90 closed head movable in said cylinder, the piston having a flange rising from said head equal in exterior diameter to that of the piston, and the flange having a plurality of 95 radial openings through it close above said head. 100

In testimony that I claim the foregoing invention, I have hereunto set my hand this 7th day of February, 1921.

LEONARD ATWOOD.
